US00D672461S

(12) **United States Design Patent**
Brogden et al.

(10) **Patent No.:** **US D672,461 S**
(45) **Date of Patent:** ** *Dec. 11, 2012

(54) **NASAL DILATOR**

(75) Inventors: **Kyle N Brogden**, Parsippany, NJ (US);
Gustav R Fenton, Parsippany, NJ (US);
Snigdha Mishra, Parsippany, NJ (US)

(73) Assignee: **GlaxoSmithKline, LLC**, Philadelphia,
PA (US)

(*) Notice: This patent is subject to a terminal disclaimer.

(**) Term: **14 Years**

(21) Appl. No.: **29/398,048**

(22) Filed: **Jul. 26, 2011**

(57) **CLAIM**

We claim the ornamental design for a nasal dilator, as shown and described.

DESCRIPTION

FIG. 1 is a perspective view of the nasal dilator showing my new design;

FIG. 2 is a top view thereof;

FIG. 3 is a bottom view thereof;

FIG. 4 is a side elevational view thereof, both sides being the same; and,

FIG. 5 is an end elevational view thereof, both ends being the same.
